UNITED STATES PATENT OFFICE.

SWITHEN C. PETTEGREW, OF MORANTOWN, KANSAS.

DEVICE FOR OILING WINDMILLS.

SPECIFICATION forming part of Letters Patent No. 657,563, dated September 11, 1900.

Application filed November 28, 1898. Serial No. 697,628. (No model.)

To all whom it may concern:

Be it known that I, SWITHEN C. PETTEGREW, a citizen of the United States, residing at Morantown, in the county of Allen, in the 5 State of Kansas, have invented a certain new and useful Device for Oiling Windmills, of which the following is a full, clear, and exact description, reference being had to the accompanying drawings, which form a part of this 10 specification.

My invention relates to a new and useful device for oiling windmills, whereby the working posts of the mill which are located at the top of the tower may be oiled by an operator 15 from the ground at the base of the tower, thus avoiding the necessity of mounting the tower to reach the oil-cups and supply the oil; and my invention consists of certain features of novelty in the construction and ar- 20 rangements of parts hereinafter described, and pointed out in the claims.

Figure 1 represents an elevation of a windmill, the tower being broken, provided with my oiling device. Fig. 2 represents a detail 25 elevation showing the manner of mounting the parts upon the windmill-head. Fig. 3 represents a detail view showing the manner of mounting and tipping the traveling oil-can. Fig. 4 represents an edge view of the track- 30 slide or traveling bracket. Fig. 5 represents a cross-section on line XX of Fig. 4, showing the manner of connecting the traveling oil-can with the bracket. Fig. 6 represents a top view of the stationary oil-can.

Similar numerals refer to similar parts 35 throughout the several views.

1 represents a windmill-tower. 2 represents the windmill-head, mounted on the turn-table 3 on the tower in the usual 40 manner.

4 represents the wind-wheel shaft, on which is mounted the wrist-plate 5.

In the mill shown in the drawings the pump-staff is operated by a connecting-rod 6, 45 extending above the wind-wheel or driving shaft and working in the elevated guide-block 7 and operated by the pitman 8, mounted on the wrist-pin 9 of the wrist-plate 5.

This is a quite usual and familiar form of 50 mill-head; but as will appear my oiling device may be applied with equal facility to any mill-head of usual form and construction.

10 represents the several oil-cups for oiling the working parts of the mill.

11 represents a stationary oil-can mounted 55 on the arm 12, secured upon the guide-block 7, and thereby raised above the bearings of the mill to which it is desired to apply the oil. Said can is provided in its bottom with the spouts or conveyers 13, extending to and ar- 60 ranged to deliver oil into the oil-cups 10 and other working bearings of the mill, as to the bearing of the connecting-rod in its guide-block and the bearing of the mill-head upon the turn-table. The top of said can is cov- 65 ered, one portion of the cover being hinged, as shown at 14 in Fig. 6. A weight 15 is connected by the arm 16 with the hinged portion of the cover, and a lip 17, secured to the body of the can, extends over the same, the 70 weight acting to retain the hinged portion in elevated position against the lip and close to the mouth of the can. A keeper 18 is pro- 75 vided for the arm 16 of the weight.

19 represents an arm secured to the guide- 75 block 7, on which is mounted a block 20.

21 represents a track or way consisting of a pair of parallel wires connected with the block 20 and extending to the ground at the base of the tower. The ground end of the 80 wires forming the track may be connected with a cross-bar 35, provided with lugs or hooks 36, arranged to engage a cross-piece of the framework of the tower, and thus hold the track and give it stability as the travel- 85 ing oil-can is drawn up thereon. When not in use, the cross-bar 35 is detached from the framework of the tower, and the track swings free, being unconnected with the tower, and is thus permitted to follow the windmill-head 90 as it turns in the wind.

22 represents a traveling oil-can carried by the gudgeons 23 in the wings 24 of the brackets 25, which embrace and are arranged to travel on the track. As shown in Figs. 4 and 95 5, the gudgeons are provided with an elongated cap 26 and elongated openings 27 pro- 100 vided in the wing for its insertion, the relation being such that when the can stands up- right the caps will be across the openings, so that when the can is hung in the brackets the wires of the track will be held in their proper relation and the can cannot escape.

28 represents a cord secured at one end to

the ring 29, attached to the can at or near its bottom, and passing over the pulley 30, attached to the block 20, the other end is brought back to the hand of the operator. This cord 5 is not all shown, it being familiar to pass a rope over an elevated pulley. By this cord the can is drawn up on the track, a spring-arm 31 being provided on the can extending beyond and bearing against one of the track- 10 wires to prevent tilting the can as it travels up the track. Near the top of the track are provided the stops 32 to limit the upward movement of the can. A trip-arm 33 extends below the stops parallel with the track such 15 distance as to engage the spring-arm 31 and release the same from the wire and permit the can to tilt just before or as the brackets reach the stops, as shown in dotted lines in Fig. 2, and the relation of the parts being 20 such that the nozzle of the can will reach the stationary can a sufficient pull on the cord as the traveling can is tilted will press the nozzle upon the lid of the stationary can and overcome the resistance of the weight, and the 25 contents of the traveling can will be discharged into the stationary can and thence distributed through the spouts 13 to the several oil-cups and bearings. The traveling can being emptied, a weight 34 is provided on 30 its bottom inner edge, so that upon releasing the cord the can will resume its upright position and by gravity return down the track.

Thus is provided a simple, convenient, and economical means for oiling the working parts 35 of the mill without taking the time and trouble to mount the tower every time the mill must be oiled, and it is obvious that with this device the mill will be oiled much more frequently and the bearings kept in much 40 better condition than where it is necessary to climb to the top of the tower to do the oiling, and thus the working parts being more properly oiled the life of the mill is greatly prolonged.

45 It is apparent that with slight modifications in details the device may be applied to any windmill or to any other machinery where there are elevated bearings to be oiled.

Having thus fully described my device, 50 what I claim as my invention, and desire to secure by Letters Patent, is—

1. A device for oiling windmill-bearings

consisting of a stationary can mounted above the bearings, provided with spouts leading to the oil-cups and bearings, a track or way having one end mounted above said stationary can, brackets arranged to travel on said track, a traveling oil-can pivotally mounted between said brackets, a spring-arm mounted upon said traveling can and arranged to bear 60 against the track to prevent the tilting of the can, a trip-arm secured upon the track in the path of said spring-arm to release the same from the track at such point that as the release is made the can will be tilted and discharge its contents into the stationary can, and means for propelling said traveling can upon its track, substantially as set forth.

2. In a device for oiling windmill-bearings a track having one end mounted above the 70 bearings, brackets arranged to travel on said track, an oil-can pivotally mounted between said brackets, a spring-arm mounted upon said can and arranged to bear against the track to prevent tilting of the can, a trip-arm 75 secured upon the track in the path of said spring-arm to release the same from the track, a cord secured to the can and passing over an elevated pulley for elevating the can and tilting the same when said spring-arm is released, and a weight on the can for restoring the same to upright position and returning it 80 down the track, substantially as set forth.

3. In a device for oiling windmill-bearings, 85 a track consisting of two parallel wires, winged brackets embracing said wires and arranged to travel thereon, an oil-can provided with oppositely-disposed gudgeons arranged to engage elongated openings in said bracket-wings, and elongated caps on said gudgeons 90 to prevent escape from said openings, substantially as set forth.

4. In a device for oiling windmill-bearings, 95 an oil-can mounted above the bearings and provided with a marginal lip, a weighted hinged cover on said can arranged to be opened inwardly and to close against said lip, and spouts on said can leading to the oil-cups and bearings, substantially as set forth.

SWITHEN C. PETTEGREW.
